FENCE STRETCHER OR HOIST

George Washington Benjamin, Muncie, Ind., assignor to Kitselman Brothers, Muncie, Ind., a corporation of Indiana

Application March 27, 1940, Serial No. 326,119

6 Claims. (Cl. 254—75)

My invention relates to wire-stretchers or hoists of the type in which a chain is pulled through a body member by means of force-multiplying mechanism including a manually oscillatable lever 5 pivotally mounted on the body and provided with pawls which co-operate with the chain.

The primary objects of my invention are to produce a device of the type described in which, for any given amplitude of lever oscillation, the 10 mechanical advantage will be greater than in other devices of which I am aware and to produce a chain hoist in which the load can be released under control by the operating lever.

In carrying out my invention in its preferred 15 form, I employ a twisted-link chain in which adjacent links are similarly oriented with reference to the chain-axis. The body of the device is formed with an opening which extends longitudinally through it and in which the chain is 20 freely slideable. The operating lever is pivotally mounted on the body; and, on opposite sides of its axis of pivotal mounting, carries a pair of pawls arranged to engage the chain from opposite sides thereof. Acting between the pawls 25 is a spring which, when the device is being used under load, serves to draw the pawls toward each other into engagement with the chain. To adapt the device for effecting a controlled release of the load, I provide means acting between the operating 30 lever and an intermediate point of this spring, such means acting to alter the manner in which the spring acts on the pawls and thereby to adapt the device for controlled release under load in a manner which will be explained more fully 35 hereinafter.

The accompanying drawings illustrate my invention: Fig. 1 is a side elevation of the device arranged for use in stretching a wire; Fig. 2 is a view similar to Fig. 1 but on a larger scale, with 40 parts of the device broken away and shown in section and with the operating lever in a different position; Fig. 3 is a view similar to Fig. 2 showing one condition existing when the device is operating to effect a controlled release of the load; Fig. 4 is a bottom plan view corresponding to 45 Fig. 3; Fig. 5 is a section on the line 5—5 of Fig. 3, but showing the device arranged for operation under load; Fig. 6 is an end elevation of the body illustrating the cross-sectional shape of the 50 chain-receiving opening therein; Fig. 7 is a view similar to Fig. 2, but showing a modified form of pawl-actuating spring acting as it does when the device is operating under load; Fig. 8 is a view similar to Fig. 7, but showing a condition existing 55 when the device is operating to effect a con-

trolled release of the load; Fig. 9 is a section on the line 9—9 of Fig. 8.

The body 10 of the device may take any convenient form, that illustrated in the drawings being T-shaped in elevation and provided with a 5 U-shape yoke 11 adapted for connection to one of the objects between which the device is to operate. The body 10 is provided with an opening extending longitudinally through it, such opening slidably receiving a chain 12. Conveniently, an intermediate point of the chain 12 is secured to the yoke 11, leaving one end of the chain free to be wrapped around an object, such as the post 13, against which the force exerted by the device will react. Desirably, the ends 15 of the chain are provided with hooks 14, one for engagement with the yoke 11 and the other for connection to the load. As shown in Fig. 1, the latter hook 14 engages a wire-gripper 15 gripping a wire 16 which is to be stretched, but it is to be 20 understood that the load applied to the chain may be of any kind.

The chain illustrated in the drawings is made up of twisted links so formed that adjacent links will be similarly oriented with reference to the 25 axis of the chain. The opening through the body 10 is so shaped in cross-section, as by being provided with longitudinally extending ribs 17 in its sides, that it will hold each link of the chain 30 in fixed angular position about the chain axis 35 relative to the body 10.

The operating lever 20 has secured to it a pair of arms 21 which receive the body 10 between them. Desirably, there is interposed between the respective arms 21 and the body 10 a pair of 35 plates 22 and 23 which are rigid with the arms 21. A pair of pins 24, each extending through one of the arms 21 and the associated plate, serve to pivotally interconnect the operating lever 20 with the body 10. If desired, the pins 24 may be 40 formed as machined bosses on the sides of the body 10; but however they are formed, their axis is substantially co-planar with the center line of the chain 12 within the body.

At equal distances from and on opposite sides 45 of the pins 24 there are mounted between the arms 21 a pair of pawls 26 and 27 having teeth 26' and 27' projecting toward each other through slots 28 in the body 10 into association with the chain. Each of the pawls 26 and 27 is 50 conveniently mounted upon a bolt 29 extending between the arms 21. Each of the teeth 26' and 27' is shaped to enter the chain-links, has a front face which is approximately perpendicular to the center line of the chain and an oblique rear face 55

which serves to cam the tooth out of the chain-link as the associated pawl moves rearwardly relatively to the chain 12, all as will be clear from Fig. 2.

5 The pawls 26 and 27 are freely swingable about the bolts 29 on which they are respectively mounted and are normally held in engagement with the chain 12 by a spring acting between them. In the device illustrated in Figs. 1 to 5, 10 the spring acting between the pawls is an open-wound tension spring 32 the ends of which are formed into hooks engaging the bosses 33 on the pawls. As shown, the spring 32 is located on the same side of the body 10 as the plate 23, and 15 the forward portion of that plate is desirably offset outwardly to form a protective housing for the spring.

In Fig. 1, the device is shown as operating to apply tension to the wire 16, the handle being 20 shown at the mid-point of a swing to the right. In this condition, the tooth 26' on the pawl 26 is disposed within one link of the chain and is moving the chain forwardly, or to the left, in the body 10. The pawl 27 is moving to the right, or 25 rearwardly, the inclined rear surface of the tooth 27' camming the tooth outwardly against the force exerted on the pawl 27 by the spring 32. A position somewhat nearer the limit of rightward movement of the handle 20 is illustrated in 30 Fig. 2. In the position there illustrated, the teeth 26' and 27' have passed each other; and from Fig. 2 it will be apparent that as rightward movement of the handle 20 continues the pawl 26, and the chain with it, will move to the left and 35 the pawl 27 to the right until the tooth 27' enters the chain link immediately behind that in which the tooth 26' is located. When this occurs, the handle 20 will be substantially at the limit of its swing to the right; and upon a succeeding swing 40 to the left the pawl 27 will move forwardly carrying the chain with it, while the pawl 26 moves rearwardly, being cammed outwardly away from the chain by the inclined rear face of the tooth 26'.

45 It is to be noted that because of the use of the twisted-link chain the pawls 26 and 27 may have the simple opposed relationship illustrated while still operating to advance the chain one link for each complete swing of the operating lever 20. If the chain 12 were formed of plane, or untwisted, links, only alternate links would be similarly oriented; and with the pawl arrangement illustrated it would then be necessary to advance the chain two links at each swing of 50 the lever 20. This would necessarily involve either a reduction in the mechanical advantage or a reduction in the size, and therefore in the strength, of the chain. With the twisted link chain, however, the opposed teeth 26' and 27' 55 engage in adjacent links, and it is therefore possible to advance the chain but one link for each swing of the operating lever 20.

Because of the inclined rear face of the teeth 26' and 27', the chain 12 can always be freely 60 pulled forwardly through the body 10. To make it possible to draw the chain freely through the body in the opposite direction, each of the pawls 26 and 27 may be provided with a rearward extension 35. By grasping these two extensions 35 65 between the thumb and forefinger, the pawls 26 and 27 may be swung apart in opposition to the spring 32, thus moving the teeth 26' and 27' out of association with the chain so that free rearward movement thereof within the body 10 will 70 be permitted.

75 It will be noted that in the normal operation of the device to advance the chain under load, the forward pawl is not disengaged from the chain until after the rearward pawl has entered into a chain-link and assumed the load. As a result, the device is positive in operation and will always act to prevent accidental release of the load, even if the chain should be stretched to increase the length of each link and the angle through which the handle must be swung at each 10 operation. If the handle is released with the device under load, the pawl carrying the load will move rearwardly, and the other pawl will move forwardly and enter the chain; and a condition of equilibrium will ensue in which, with the 15 handle in one or the other of its extreme positions, the load is positively held and divided substantially equally between the two pawls. Should the operator's hand slip from the handle while making a stroke thereof, or should the 20 handle break, the device will assume the equilibrium position just described, and the chain will be positively held by both pawls from slipping through the body.

To adapt the hoist illustrated in Figs. 1 to 5 25 for use in effecting a controlled release of a load on the chain 12, I employ a spring 32 which is open-wound, and I provide means for interconnecting an intermediate point of that spring with the operating lever. This means may take the 30 form of a T-shaped member 38 the cross-bar of which is disposed within the spring 32 and the other arm of which projects outwardly between adjacent turns of the spring near the longitudinal center thereof, as will be clear from Fig. 2. The 35 plate 23, at a point opposite the pivot 24, is provided with a slot 39 (see Figs. 1 and 3) for the reception of the central arm of the T. When the device is being used to advance the chain under load, the central arm of the T 38 occupies the 40 position illustrated in Figs. 1, 2, and 5, where it does not interfere with the action of the spring 32 in drawing the pawls 26 and 27 toward each other. When, however, the device is used to effect a controlled release of the load (i. e., a controlled rightward movement of the chain 12 in 45 the body 10) the central arm of the T 38 occupies the slot 39, as shown in Figs. 3 and 4, thus serving to limit the movement of the central portion of the spring 32 relative to the operating 50 handle.

When the device is to be changed from load-advancing to load-releasing condition, the operating handle is brought into or near its mid-position, under which circumstances the slot 39 55 will be opposite the mid-point of the spring and the central leg of the T 38 can be swung into such slot. If it be assumed that the pawl 26 is carrying the load, as it is in Figs. 2 and 3, the handle is now permitted to move to the left causing a controlled rightward movement of the chain. As will be clear from Fig. 3, which shows the device with the handle almost at the leftward limit of its movement, such leftward movement of the handle will move the T 38 toward 60 the load-carrying pawl 26 and will thereby place the upper half of the spring 32 in compression and cause it to exert on the pawl 26 a force tending to move that pawl away from the chain. The load on the chain 12 holds it in engagement with the forward face of the tooth 26' and creates sufficient friction to prevent the pawl 26 from moving outwardly under the force exerted upon it by the compressed upper portion of the spring 32. While the tooth 27', under the influence of 75

the stretched lower half of the spring 32, has entered the chain-link immediately ahead of that within which the tooth 26' is located, its front face has not yet been engaged by the chain.

- 5 When leftward movement of the handle is continued beyond the point shown in Fig. 3, the pawl 27 is moved forwardly and the pawl 26 rearwardly, and the chain will move rearwardly with the pawl 26 until it engages the pawl 27. 10 This creates the condition of equilibrium above referred to. If the handle is now moved through a slight distance further to the left, the pawl 27 will advance the chain slightly, whereupon the tooth 26' will be relieved of the load and the 15 compressed upper portion of the spring 32 will move the pawl 26 outwardly until the tooth 26' clears the chain, as is indicated by the dotted-line position. The load is now being applied to the operating handle through the tooth 27' and the pawl 27; and as the operating lever 20 is permitted to move to the right at a controlled rate of speed, the chain 12 will move rearwardly in the body 10 while the pawl 26 moves forwardly. During its initial forward movement, the pawl 26 20 is held out of engagement with the chain by the compressed upper portion of the spring 32, which continues to exert an upward force on the pawl 26 until after it has cleared the chain-link within which it had previously been located. As the 25 operating handle approaches the mid-point of the swing to the right, all parts of the spring 32 will again be under tension; but the tooth 26' will be prevented from entering the link immediately ahead of that which it had previously engaged by reason of the presence therein of the tooth 27', which projects far enough through the chain for this purpose. As the operating handle approaches the rightward limit of its movement, the lower half of the spring 32 will be compressed 30 and will exert on the pawl 27 a force which will tend to move that pawl out of engagement with the chain but which will be insufficient to overcome the friction between the tooth 27' and the chain. At the extreme rightward limit of movement of the operating handle, the pawl 26 will be fully advanced, the tooth 26' will have engaged the chain, the tooth 27' will thereby be freed of load, and the compressed lower portion of the spring 32 will move the pawl 27 downwardly to cause disengagement of the tooth 27' from the chain and to permit the succeeding leftward swing of the operating handle. 35

In the device illustrated in Figs. 7 to 9, I have employed a different form of spring. The spring there shown consists of a central eye portion 40 formed of one or more turns of spring wire the ends of which cross adjacent the eye, are bent to provide two generally parallel portions 41, and are again bent to re-cross, the extreme ends of the wire being respectively attached to the pawls 26 and 27. 45

The spring illustrated in Figs. 7 to 9 is so shaped that it normally operates to draw the free ends of the pawls 26 and 27 toward each other, exactly as does the spring 32 in the device previously described. As the operating lever is oscillated, the eye 40 and parallel legs 41 of the spring swing back and forth in a space between one of the arms 21 and a plate 42 which is secured to the arms by the bolts 29. To connect the spring 40—41 to the operating lever, and thereby adapt the device to effect a controlled release of a load, I mount in the plate 42 a screw 43 which, when retracted out of the plane of the spring, does not interfere with the free movement thereof but which, when ad-

vanced, enters the space between the two legs 41 of the spring and limits the movement thereof relative to the operating handle, as will be clear from Fig. 8. From a comparison of the respective spring-positions shown in Figs. 7 and 8, both 5 of which show the operating handle approximately at the leftward limit of its movement, it will be apparent that as each of the pawls 26 and 27 approaches the rearward limit of its movement the spring will exert an outwardly directed force upon 10 it so that when the load on the chain 12 is transferred from the rear pawl to the forward pawl the spring will operate to force the former outwardly away from the chain. This action of the spring is illustrated in Fig. 8, where the pawl 26 is shown 15 in full lines in the position it occupies immediately before being relieved of load and in dotted lines in the position it occupies after the load has been transferred to the pawl 27. 20

I claim as my invention:

1. In a device of the type described, a body having a longitudinally extending guide-way for a chain, a chain slideable in said guide-way, an oscillating operating lever pivotally mounted on said body on an axis perpendicular to said chain, 25 a pair of pawls pivoted to said operating lever on opposite sides of its axis of pivotal mounting and extending forwardly of said body on opposite sides of the chain, the front end of each pawl being provided with a tooth adapted to enter a chain-link and having an oblique rear face adapted to cam the tooth out of the chain-link as the associated pawl moves rearwardly relative to the chain, a spring normally acting directly between said pawls and urging them toward each other 30 and inwardly of the body, and means operable at will to connect an intermediate point of said spring to said operating lever, said spring being so formed that when it is connected to said operating lever it will urge each pawl inwardly as 35 the pawl approaches the forward limit of its movement and outwardly as it approaches the rearward limit of its movement.

2. The invention set forth in claim 1 with the addition that said spring is an open-wound helical spring disposed forwardly of the pawl-pivots and having its ends connected respectively to said pawls, said connecting means acting when operative to limit axial movement of the center portion of said spring relative to said operating lever 45 whereby the end portion of the spring between said connecting means and each pawl will be compressed as such pawl approaches the rearward limit of its movement.

3. In a device of the type described, a body having a longitudinally extending guide-way for a chain, a chain slideable in said guide-way, an oscillating operating lever pivotally mounted on said body on an axis perpendicular to said chain, a pair of pawls pivoted to said operating lever on 60 opposite sides of its axis of pivotal mounting and extending forwardly of said body on opposite sides of the chain, the front end of each pawl being provided with a tooth adapted to enter a chain-link and having an oblique rear face adapted to 65 cam the tooth out of the chain-link as the associated pawl moves rearwardly relative to the chain, yielding means acting on said pawls, and a controlling device associated with said yielding means and selectively operable to cause said 70 yielding means either to urge both pawls inwardly at all times or to urge each pawl inwardly when in and near the forward limit of its movement and outwardly when in and near the rearward limit of its movement. 75

4. In a device of the type described, a body having a longitudinally extending guide-way for a chain, a chain slideable in said guide-way, a pair of pawls disposed on opposite sides of said chain and provided with teeth projecting inwardly and adapted to be received in links of the chain, means mounted on said body for alternately advancing each pawl while simultaneously retracting the other, yielding means acting on said pawls, and a controlling device associated with said yielding means and selectively operable to cause said yielding means either to urge both pawls inwardly at all times or to urge each pawl inwardly when in and near the forward limit of its movement and outwardly when in and near the rearward limit of its movement.

5. The invention set forth in claim 4 with the addition that said chain is formed of twisted links, adjacent links being similarly oriented with reference to the axis of the chain.

6. In a device of the type described, a body having a longitudinally extending guide-way, a pair of pawls disposed on opposite sides of said guide-way and provided with inwardly projecting teeth adapted to extend thereinto, a tension element 5 slideable in said guide-way and having a longitudinally extending series of openings each of which is adapted to receive the tooth on one or the other of said pawls, means mounted on said body for alternately advancing each pawl while 10 simultaneously retracting the other, yielding means acting on said pawls, and a controlling device associated with said yielding means and selectively operable to cause said yielding means either to urge both pawls inwardly at all times 15 or to urge each pawl inwardly when in and near the forward limit of its movement and outwardly when in and near the rearward limit of its movement.

GEORGE WASHINGTON BENJAMIN. 20
